(57) **CLAIM**

The ornamental design for a part of indoor unit for air conditioner, as shown and described.

DESCRIPTION

The patent or application file contains at least one drawing executed in color. Copies of this patent or patent application publication with color drawing(s) will be provided by the Office upon request and payment of the necessary fee.

1. Part of indoor unit for air conditioner
2. Part of indoor unit for air conditioner
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom

Fig. 1.1 to fig. 1.7, and fig. 2.1 to fig. 2.7 show a part of indoor unit for air conditioner according to different embodiments of the present design, respectively; The part of indoor unit for air conditioner is used for regulating temperature.
